UNITED STATES PATENT OFFICE.

JOHN H. FITZGERALD, OF ROCKY FORD, COLORADO.

PORTABLE HOLD-UP DAM.

1,318,656.

Specification of Letters Patent.

Patented Oct. 14, 1919.

Application filed July 25, 1917. Serial No. 182,712.

To all whom it may concern:

Be it known that I, JOHN H. FITZGERALD, a citizen of the United States, residing at Rocky Ford, in the county of Otero, State 5 of Colorado, have invented certain new and useful Improvements in Portable Hold-Up Dams; and I do hereby declare the following to be a full, clear, and exact description of the invention, such as will enable others 10 skilled in the art to which it appertains to make and use the same.

This invention relates to an appliance designed particularly for use in connection with land irrigation systems and is directed 15 more particularly to a device that may be aptly termed a portable hold-up dam.

In carrying out the present invention it is my primary purpose to provide an appliance of the above character the use of which will 20 obviate the necessity for the construction of mud dams or cut-arounds when it is desired to direct all or a percentage of the water in the main ditch, into a cross ditch for the purpose of irrigating a certain area, it 25 having been found that these mud-dams or cut-arounds are under certain conditions, lacking in efficiency and hence unsatisfactory.

A further purpose of the present invention 30 is to provide an appliance that is simple, durable and inexpensive in construction; is light in weight and collapsible so that it may be conveniently carried; may be quickly and readily installed or removed from a ditch, 35 and embodies means through the medium of which the quantity of water passing through the main and cross ditches may be accurately regulated.

With the above and other objects of similar nature in view, the invention consists in 40 the construction, combination and arrangement of parts, set forth in and falling within the scope of the appended claims.

In the drawings:—

45 Figure 1 is a top plan view of the appliance properly positioned with respect to a main and a cross ditch of an irrigation system, with the handle in lowered or inoperative position.

50 Fig. 2 is a front view thereof with the outlet opening partially uncovered, and the handle raised.

Fig. 3 is a view looking from the opposite side of Fig. 2 with the outlet entirely un-

covered, the handle also being shown lowered, and

Fig. 4 is a perspective view of the appliance removed from the ditch.

Referring now more particularly to the accompanying drawing, there is shown the 60 main ditch A and a cross ditch B of an irrigation system, the invention being illustrated generally at C as properly positioned for use with relation to said ditches.

The appliance C consists preferably of a 65 rectangular sheet 5 of canvas or other flexible, durable and water proof material, the dimensions of said sheet being approximately the same as the cross dimensions of the ditch into which the device is to be 70 placed. The upper edge portion of the sheet 5 is suitably secured to a transverse supporting bar or member 6 as for instance by means of metal strips 7 between which strips and said bar the sheet 5 is disposed and held 75 by means of suitable fastening means such as tacks 8, or the like disposed to connect the strips, sheet and bar. The ends of the transverse bar 6 extend a short distance beyond the adjacent vertical side edges of the sheet 80 5 and are adapted to rest upon the banks of the ditch in which the device is located whereby to support the latter in position.

The sheet 5 at its vertical center and adjacent its upper edge is formed with an outlet opening 9 and is reinforced by means of plates 10 disposed on the respective sides of the sheet and having therein openings 11 registering with the opening 9. The plates 10 are preferably made up of a single section rebent intermediately of its ends and secured to the fabric sheet 5 and also to the bar 6 by the fastening means 8, the same as the strips 7, as indicated while one of them is equipped with parallel guide elements 12 95 having offset portions disposed in spaced relation thereto and at opposite sides of the outlet opening. There is slidably mounted in these guide elements 12 to cover and uncover the opening 9 and in consequence regulate the passage of water through the latter, a door 14 the upper edge of which is formed with a suitable hand grip 15.

With the water traveling in the main ditch A, as indicated by the arrows, the 105 divide is positioned, as illustrated, at the junction of the main and cross ditches A and B respectively, it being supported at its

upper edge by reason of the transverse bar resting upon the banks of the main ditch while it is equipped at its lower corners with stakes 16, attached to the sheets by means 5 of ropes 17, and is drawn tightly across and to the bottom of the main ditch and held securely in place by driving said stakes into the ditch walls as will be readily understood.

10 With the appliance so arranged, in order to direct all or only a percentage of the water in the main ditch into the cross ditch, the door 14 is adjusted to regulate the size of the opening 9 and in consequence wholly 15 or partially dam, or in other words retard the flow of water in the main ditch so that it will be caused to enter and flow along the cross ditch and thus irrigate the desired area. It will be readily understood that 20 when a sufficient quantity of water has been supplied to a given area the door 14 may be entirely opened so that the water may flow freely through the main ditch, while the appliance may be quickly and conveniently lifted from the ditch and readily carried if desired to another locality, a handle 18 being provided on the supporting bar 6 for this purpose. The handle may be secured to the bar in any suitable manner, 25 such as by means of straps 19, in which the outwardly extending ends of the handle or bail are pivoted, the straps encircling and being secured to the bar, as shown.

What I claim is:—

30 1. A portable dam for irrigation systems such as by means of straps 19, in which the outwardly extending ends of the handle or bail are pivoted, the straps encircling and being secured to the bar, as shown.

35 1. A portable dam for irrigation systems consisting of a flexible sheet, having an outlet opening, a supporting bar secured to the upper edge portion of the sheet and projecting at its ends beyond the side edges 40 of the sheet, a plate secured adjacent the upper edge of the sheet having an opening registering with said outlet opening, guides on said plate, a door slidab

openings, and anchor stakes carried by the 45 lower corners of the sheet.

2. A portable dam for irrigation systems consisting of a flexible sheet having an outlet opening in the upper portion thereof, a supporting bar secured to the upper edge 50 portion of the sheet and projecting at its ends beyond the side edges of the sheet, plates secured adjacent to the upper edge of the sheet and at opposite sides thereof, said plates having openings therein registering 55 with said outlet openings, spaced guides on one of said plates and extending to the upper edges of the plates, sheet and bar, a door slidab

le in the guides to control the passage of water through said openings, a 60 handle on the bar, and anchor stakes carried by the lower corners of the sheet.

3. A portable hold-up dam comprising a flexible water-proof sheet such as canvas, said sheet having an outlet opening there-through, a supporting bar to which the upper edge portion of the sheet is secured, with the extremities of the bar projecting beyond the side edges of the sheet, strips secured to the bar over the sheet at spaced 65 points, plates secured to the sheet and comprising a section rebent over the upper edge of the sheet with its depending portions secured together and to the sheet, said plates having openings registering with the outlet 70 openings, spaced offset guide strips secured vertically to the plate at one side, a door slidab

le in the guide strips to control the passage of water through said openings and anchoring means for the lower edge of the 75 sheet.

In testimony whereof I affix my signature in the presence of two witnesses.

JOHN H. FITZGERALD.
